BOAT'S DRYDOCK

Clifton L. Rogers, Moss Point, Miss.

Application July 22, 1938, Serial No. 220,773

2 Claims. (Cl. 61—65)

The invention relates to a ship elevator, cradle and dock and more especially to a boat's drydock.

The primary object of the invention is the provision of an apparatus of this character, wherein a boat floating in a body of water can be dry-docked with ease and dispatch in that such boat can be bodily raised from the water to the necessary height for enabling repairs to be conveniently made below its water line.

10 Another object of the invention is the provision of an apparatus of this character, wherein the cradle for the boat is of novel construction in that it is susceptible of being automatically adjusted according to the hull size of the boat for 15 the holding of the same in an upright position and firmly for execution of work thereon in accordance with necessities.

A further object of the invention is the provision of an apparatus of this character, which 20 is simple in its construction, thoroughly reliable and efficient in operation, susceptible of moving the boat docked from the way therefor in said apparatus, strong, durable, and inexpensive to manufacture and install.

25 With these and other objects in view, the invention consists in the features of construction, combination and arrangement of parts as will be hereinafter more fully described, illustrated in the accompanying drawings, which disclose the 30 preferred embodiment of the invention and pointed out in the claims hereunto appended.

In the accompanying drawings:

Figure 1 is a fragmentary vertical sectional view through a water bed showing in part elevation the drydock constructed in accordance 35 with the invention.

Figure 2 is a top plan view.

Similar reference characters indicate corresponding parts throughout the several views in 40 the drawings.

Referring to the drawings in detail, A designates a portion of a water bed and B a body of water of a depth for the floating of a ship C and built in association with the bed A is the drydock 45 constituting the present invention and herein-after fully described.

The drydock comprises a fluid-operated raising and lowering plunger 10 vertically disposed and telescopically fitted within a fluid cylinder 11 50 countersunk in the bed A and this cylinder, which is closed at its bottom and open at its top, has formed at the open top an out-turned flange 12 resting upon a base slab 13 through which projects the body of the cylinder 11 and such slab 55

is partly embedded in the bed A, as is clearly shown in Figure 1 of the drawings.

Opening into the cylinder 11 are the pipes 14 and 15, respectively, each being valved at 16, and such valves are of the hand operated type. These 5 pipes 14 deliver and discharge fluid 17 under pressure to and from the said cylinder for the operation of the plunger 10 which is movable through the body of water B for raising and lowering activity. At the upper end of the plunger 10 is 10 fixed an elongated cradle 18 having at its longitudinal median a substantially V-shaped keel groove 19 and this cradle accommodates the ship C with the keel of its hull seated in the groove 19 so that when the plunger is operated the ship 15 can be raised and lowered.

Carried by the cradle 18 at opposite longer sides thereof and projected laterally therefrom are midway and outer brackets in the form of arms 20 and 21, respectively, to which are pivoted opposed fluid-operated jacks 22, their plungers 23 being pivotally connected to bracing links 24, which are pivoted at 25 to bearings 26 formed on the cradle 18, these bearings being located adjacent to the keel groove 19 and the hydraulic jacks 25 22 are operated in any suitable manner. The purpose of the jacks 22 is to hold the hull of the ship C vertically upon the cradle 18 and also to allow the quick dismissal of the ship from the cradle for the floating thereof on the body of 30 water B or to move the said ship off the drydock hereinbefore described.

The braces formed by the links 24 make contact exteriorly with the hull of the ship C when supported upon the cradle 18, as is clearly 35 closed in Figure 1 of the drawings.

What is claimed is:

1. A drydock of the character described comprising a fluid operated perpendicularly arranged raising and lowering plunger, an elongated cradle 40 fixed to the upper end of said plunger and having a keel way, vertically swinging arms pivoted to the cradle at opposite sides of the keel way for engaging a ship's hull when resting in the way, piston cylinders pivoted to said cradle at a distance outwardly with relation to said arms, pistons working within said cylinders for reciprocation therein and having pivotal connection with the said arms, a fluid cylinder having the plunger telescopically movable therein, and means for delivering fluid to and from the said piston cylinders. 45
2. A drydock of the character described comprising a fluid operated perpendicularly arranged raising and lowering plunger, an elongated cradle 50

fixed to the upper end of said plunger and having a keel way, vertically swinging arms pivoted to the cradle at opposite sides of the keel way for engaging a ship's hull when resting in the way, piston cylinders pivoted to said cradle at a distance outwardly with relation to said arms, pistons working within said cylinders for reciproca-

tion therein and having pivotal connection with the said arms, a fluid cylinder having the plunger telescopically movable therein, means for delivering fluid to and from the said piston cylinders, and means for delivering and releasing fluid to and from the fluid cylinder.

CLIFTON L. ROGERS.
